UNITED STATES PATENT OFFICE.

THOMAS JOHN JURICK, OF GREAT FALLS, MONTANA.

CIGARETTE-CASE.

1,242,699.

Specification of Letters Patent.

Patented Oct. 9, 1917.

Application filed May 17, 1917. Serial No. 169,229.

To all whom it may concern:

Be it known that I, THOMAS J. JURICK, a citizen of Austria-Hungary, and a resident of Great Falls, in the county of Cascade and State of Montana, have invented a new and Improved Cigarette-Case, of which the following is a full, clear, and exact description.

My invention relates to a cigarette case from which the cigarettes may be readily withdrawn in single succession as desired without removing the cover of the case.

An object of the invention is to provide for positioning the cigarette for convenient withdrawal and to do this with facility and despatch.

A further object is to provide an ejecting device arranged to be set and released from the exterior of the case, and adapted to partially eject a single cigarette that it may be readily grasped for withdrawal.

A more specific object of the invention is to provide an ejecting device and controlling means therefor, simple in construction and unfailing in operation and of a character to be housed, except the exterior operating devices, in a small chamber provided in the case.

The nature of the invention and its advantages will more clearly appear as the description proceeds.

Reference is to be had to the accompanying drawings forming a part of this specification in which similar reference characters indicate corresponding parts in all the views, it being understood that the drawings are merely illustrative of one example of the invention.

Figure 1 is a perspective view of a cigarette case embodying my invention:

Fig. 2 is a transverse section on the line 2—2, Fig. 3;

Fig. 3 is a longitudinal section;

Fig. 4 is a transverse section on the line 4—4, Fig. 3;

Fig. 5 is a longitudinal section taken at right angles to Fig. 3 as indicated by the line 5—5;

Fig. 6 is a front end view of the case.

In carrying out my invention in accordance with the illustrated example, a container body 10 is provided to receive cigarettes, said body having an open front end and a closed inner end or bottom 10^a, the open end being adapted to be closed by a slip cover or telescoping cover 11, the

edge of which abuts against a shoulder 12 produced by the enlarged, approximately central portion 13 of the body 10. A similar shoulder 14 is formed at the opposite side of the enlarged portion 13 against which abuts the edge of a housing 15 which slips onto the opposite end of the body. The engagement of the housing 15 with the shoulder 14 provides a housing space between the end of the housing and the closed end of the body 10 for the ejecting mechanism. The end of the cover 11 is provided with an outlet hole 16 sufficient to readily permit escape of a single cigarette, said hole being closed by a slidable cover such as a swing cover 17 pivoted as at 18 and adapted to be moved by the finger or finger nail. Within the body 10 and in line with the outlet hole 16 is an open-ended channel or trough 19 which is produced in the illustrated example by a corrugated plate 20 disposed in the body along one side thereof, the inner end of the said channel being in register with an opening 21 in the bottom 10^a of the body. The head 22 of a spring-actuated ejector 23 is adapted to protrude through the hole 21 for engaging a cigarette. The trough 19 accommodates a single cigarette which a slight shaking of the box will deposit in said trough so that an ejecting movement of the ejector when the cover 17 is swung away from the opening 16 will displace the cigarette longitudinally, causing it to protrude through the hole 16 for convenient grasping.

The ejecting device and its controlling means are carried by the housing 15 so that the placing of the housing in position on the body 10 will properly locate the ejecting head 22 at the opening 21. The ejector 23 may be in the form of a plate spring as shown, whereby to be inherently resilient, and it is fixedly secured at the end opposite the head 22 as by a rivet 24 or other means to the housing 15 at the interior of the closed end of the latter. The ejector 23 is adapted to be placed under tension by a lever 25 suitably fulcrumed between its ends on a member rigid with the housing 15, there being shown brackets 26 for the purpose. One arm of the lever 25 is pivotally connected as at 27 with an operating plunger 28 extending to the exterior of the housing 15 and provided with a suitable head 29. The free end 30 of the opposite arm of the lever 25 is deflected laterally

to overlie and bear against the ejector 23 adjacent to the head 22 thereof. To latch the ejector 23 when placed under tension by the lever 25, the ejector is adapted to be held restrained by a latch 31 rockably mounted between its ends in a bracket 32 or other fixed part on the housing 15. One arm of the latch 31 has a catch member 33 adapted to engage a side edge of the ejector 23 as best seen in Figs. 4 and 5, while the opposite arm of said latch is pivotally connected with a plunger 34 extending to the exterior of the housing, and provided with a suitable head 35. A spring 36 beneath the catch arm of the latch 31 tends to engage the same with the ejector, but the catch is releasable against the tension of the spring 36 by pressure on the head 35.

With the described construction to withdraw a cigarette from the case, the cover 17 is swung away from the opening 16 and a slight shake, if necessary, is given to the box to insure that a cigarette will gravitate into the channel 19, the case having been disposed with said channel at the lower side thereof, as in Fig. 3. Pressure exerted on the head 29 through the lever 25 will place the ejector 23 under tension and cause it to be engaged by the latch 31. An inward pressure on the head 35 will now release the ejector from the catch 31, whereby the tension of the ejector will spring the same forwardly bringing the head 22 thereof into contact with the end of the cigarette adjacent to the opening 21 so that the cigarette will be ejected or caused to protrude through the opening 16.

I wish to state in conclusion that although the illustrated example constitutes a prac-

tical embodiment of my invention, I do not limit myself strictly to the mechanical details herein illustrated, since manifestly the same can be considerably varied without departure from the spirit of the invention as defined in the appended claims. 40

Having thus described my invention, I claim as new, and desire to secure by Letters Patent:

1. A cigarette case including a container, a resilient ejector in the case adjacent to the bottom of the container and outside of the same, and adapted to displace a cigarette in a direction toward the front of the container, a lever operable from the exterior of the case and engageable with the ejector to place the same under tension, means to hold the tensioned ejector restrained, and means operable from the exterior of the case to release the tensioned ejector from the holding means. 50

2. A cigarette case including a container body having an open front end and a closed bottom formed with an opening at a side thereof, a cover for the open end of the body and formed with an outlet opening in register with the opening in the said bottom, said container having a longitudinal open-ended channel in line with the said openings, a housing removably fitting the body at the bottom thereof, an ejector carried by said housing and engageable through the opening in the bottom of the container with a cigarette in said channel, and controlling means for said ejector, said controlling means being operable from the exterior of the housing. 60

THOMAS JOHN JURICK.
